RUFUS KING, OF PLAINVILLE, MASSACHUSETTS, ASSIGNOR TO BUGBEE AND NILES COMPANY, OF NORTH ATTLEBORO, MASSACHUSETTS, A CORPORATION OF MASSACHUSETTS.

SLIDE FOR BUCKLES OR CLASPS.

1,329,085.

Specification of Letters Patent. Patented Jan. 27, 1920.

Application filed March 25, 1918. Serial No. 224,404.

To all whom it may concern:

Be it known that I, RUFUS KING, a citizen of the United States, residing at Plainville, in the county of Norfolk, State of Massachusetts, have invented certain new and useful Improvements in Slides for Buckles or Clasps, of which the following is a specification.

My invention is an improved slide for use with buckles or clasps employed for securing together straps or bands of webbing attached to wrist-watches. The object of my improvement is to provide a slide for this purpose which, while being adjustable longitudinally of the strap or webbing, is at the same time adapted to frictionally grip the latter to hold it securely against unwaranted movement thereon. Another and most important object of the improvement is to provide a slide which may be readily and easily slipped on over any portion of the strap or band whereby to render it more convenient for application or removal.

The manner and means for carrying out these improvements are fully described in the following specification, illustrated by the accompanying drawings, in which like reference characters designate like parts. In the drawings:

Figure 1 is a view showing my improved slide applied to a band or strap of webbing which has the usual buckle or clasp at its end;

Fig. 2, a plan view of the slide showing the manner of inserting the strap through the opening in its end, whereby the latter may be passed over and under the cross-bars;

Fig. 3, a similar view showing the strap or band entered in the slide to a slightly farther extent;

Fig. 4, a side view showing the strap being entered in the slide as illustrated in Fig. 2;

Fig. 5, an end view of the slide with the strap shown in the same relation;

Fig. 6, an end view corresponding to Fig. 3; and

Fig. 7, an end view of the slide showing the strap in section to illustrate the manner in which it is gripped by the end-bars of the slide.

My improved device is intended for use particularly with the relatively thick, heavy khaki straps worn by sailors and soldiers for attaching watches to their wrists. It is 55 also adapted, however, for use with leather straps and with ribbons for ladies' watches. Referring to Fig. 1, B designates a strap of knitted, netted or woven fabric which is looped through an opening in a buckle or 60 clasp-member C; and S is the slide which embraces the sides of the strap or band B and is adjustable longitudinally thereof. As shown more particularly in Figs. 2 and 3, the slide S comprises a substantially flat 65 plate of rectangular outline having side-members s, s connected by a central cross-bar 2. Extending at right-angles to the side-members s, s are end-bars 3, 3 arranged in parallel, spaced relation with the central 70 cross-bars 2. It is to be noted that the bars 3, 3 are not continuous clear across the slide but are interrupted or cut away at the center to provide openings 4, 4 between their inner ends. The opposed extremities of the bars 75 or arms 3, 3 are preferably rounded and bent or curled upwardly at 5, 5, see Figs. 5 to 7.

As shown in Figs. 4 and 5, the central cross-bar 2 is raised slightly above the plane of the side-members s, s and the end-bars 80 3, 3 so that the strap or band B can pass beneath it, see also Fig. 1. Projecting upwardly from the bar 2 are two studs or posts 6 having spherical ends 7 adapted to snap into suitable openings 8 in the buckle or 85 clasp-member C. The openings 8 are formed in the under plate c of the clasp C which is constructed with suitable slits 9 to provide for the expansion of the sides of the openings as they snap over the balls 7 on the 90 studs 6. While I have herein shown and described a preferred form of clasp-member C, this element forms no part of the present invention, but is illustrated to show its method of coöperation with the slide-member S.

Heretofore, with this type of clasp or buckle, the slide S has usually been provided with three uninterrupted cross-bars for embracing the sides of the strap or band B. 100 Unlike the present improved device, however, the cross-bars or end-members of the

slide have been made continuous so that in applying the strap to place it is necessary to thread its end through the slits between the cross-bars. This required the placing 5 of the slide on the strap before the ends of the latter were doubled over and sewed together to provide the loops by which the buckle is fastened at one end and the watch at the other. One object of the present im- 10 provement is to provide a slide which can be slipped on over any portion of the strap or band B after the latter has been looped over at its ends, and the manner of accom- plishing this purpose will now be explained. 15 The method of applying my improved slide to use is shown particularly in the enlarged views, Figs. 2 to 7, and is as follows: In at- taching the slide to the strap or band B the edges of the latter are pinched together be- 20 tween the fingers and entered through one of the openings 4 between the ends of the bars 3, 3. By pulling the strap upwardly as illustrated in Fig. 3, its marginal edges will then be spread outwardly to slide into place 25 to fill the slit 10, see Figs. 5 and 6. In Figs. 2 to 4 one side of the strap B is shown as having been entered in the slit 11 of the slide S, and after it has been pulled up through the opening 4 at the other end of the 30 slide, as illustrated in Figs. 2 and 3, it is drawn taut to spread it out to its full width as shown in Fig. 1. When in place, the strap B passes over the two bars 3, 3 at one end of the slide, beneath the central cross- 35 bar 2, and up over the bars 3, 3 at the op- posite end. Referring now to Fig. 7, when the strap B lies in this position the upturned ends 5, 5 of the cross-bars 3, 3 will indent into its under surface and provide a grip- 40 riting action which tends to prevent unwarranted movement of the slide on the strap. To allow the slide S to be slid along the strap, to adjust it in position thereon, it is only necessary to loosen the strap so that 45 it will be free from the upturned edges 5, 5 of the end-bars 3, 3. When the tension on the strap is released in this manner the slide can be moved freely along its length, but as soon as the strap is drawn taut again 50 it will automatically bind against the relatively sharp edges of the end-bars 3, 3 to cause the latter to frictionally grip its sur- face to prevent unwarranted movement. 55 I am aware that it is old in the art to pro- vide a slide for buckles and clasps con- structed with cross-bars over and under which the strap or band passes to hold the slide in place thereon. As before explained, however, with this known type of slide it is 60 necessary to thread the strap through the relatively narrow slits or openings between the cross-bars, and with bulky material, such as textile fabrics, this has been found to be a difficult and awkward operation. That is to say, it is not easy to insert the ends of the

strap through the slits, particularly when the ends have been doubled over to form the loops. With my present improved arrange- 70 ment, the slide can be applied to any portion of the strap after the ends of the latter have been doubled over into loops, and with much greater ease and convenience. In other words, it is not necessary to thread the strap through the slide since it can be entered in place in the slits between the cross-bars by 75 doubling its marginal edges together and pulling it through the openings 4. This operation is very simple and easy to per- form, and the strap assumes its natural posi- 80 tion automatically when its ends are pulled out taut. Furthermore, since it is not neces- sary to thread the strap through the slits between the cross-bars, these slits may be made narrower. That is to say, the bars can be placed closer together so that they will grip 85 the strap more securely and the whole slide is thereby made smaller and much neater in appearance. In addition to the above de- scribed feature of easy application of the 90 slide to the strap I have also provided a fur- ther improvement as regards its gripping or holding efficiency. The upturned edges of the end-bars 3, 3 provide teeth or detents which bite into the surface of the strap or band to prevent accidental or unwarranted 95 movement of the slide when the band is drawn taut. Through this arrangement the slide takes a much more secure grip on the strap, and after it has once been adjusted in place on the wearer's wrist it will be held 100 snugly and prevented from becoming loose and slipping.

Various slight modifications might be made in the form and construction of my device without departing from the spirit or 105 scope of the invention; therefore, without limiting myself to the exact embodiment shown and described, what I claim is:—

1. An improved buckle-slide for wrist- 110 straps and bands of webbing consisting of a substantially rectangular plate having op- 115 posite side-members connected by a central cross-bar, and end-bars arranged in parallel spaced relation with the central cross-bar, both of said end-bars being cut away at the center to provide openings through which the strap may be entered by doubling its edges together in the manner and for the purpose substantially as described.

2. An improved slide for use with the 120 buckles or clasps of wrist-straps consisting of a substantially flat plate of rectangular outline having opposite side-members and three spaced-apart cross-bars extending laterally therebetween, with the two opposite 125 end cross-bars divided at the center to pro- 130 vide openings through which the strap may be entered to pass it over and under the cross-bars whereby the slide is applied thereto to adapt it for adjustment therealong.

3. An improved slide for wrist-straps of webbing consisting of a relatively flat rectangular plate having opposite side-members with a central cross-bar extending therebetween, and end-bars arranged in parallel spaced-relation on either side of the cross-bar and cut away at the center to provide openings for the insertion of the strap, the opposed extremities of the end-bars being adapted to frictionally grip the strap ¹⁰ when the latter is applied to the slide by passing it over and under the cross-bars.

In testimony whereof I affix my signature.

RUFUS KING.
